APPARATUS FOR CONDITIONING FUEL OIL

Peter J. Vanderlip, Lansing, Mich.

Application February 26, 1953, Serial No. 338,966

3 Claims. (Cl. 158—36.3)

This invention relates to apparatus for conditioning heavy grades of fuel oil for use in an oil burner by reducing their viscosity to a point affording proper utilization thereof in the atomizing means.

So-called residual fuel oils are preferred for their low cost but, in order to derive maximum efficiency therefrom, rotary type fuel oil burners have been found most suitable. Moreover, many installations are equipped with burners for the lighter grades of oil and, with increases in the purchase price of these oils, the consumer often changes over to the heavier, but cheaper, grades. However, there then arises the problem of reducing the viscosity of the heavier oil to correspond to that of the lighter fractions. Such end is most easily achieved by heating the oil in an intermediate supply tank inside the premises and, in nearly all such cases, electrical heating elements of the immersion type have been employed. However, the cost of electricity is often such that the price advantage of the heavier fuel is outweighed by the cost of the electricity consumed.

It will be recognized that other factors being equal, the cost of hot water or steam taken from the heating plant on the premises will be much less than purchased electric power. Accordingly, the principal object of my invention is to provide apparatus for reducing the viscosity of a fuel oil which will yield the intended end product both prior to, and during, operation of the boiler by utilizing electric power during the periods when the boiler is unable to provide fluid medium for the purpose, and by utilizing such medium when the same is available in sufficient volume.

Another object resides in the attainment of the foregoing desideratum by fully automatic means.

Still another object is to provide apparatus as aforesaid which includes means for circulating the preheated oil between the main storage tank and the intermediate or reserve tank to maintain continuously a proper fluid state of the incoming oil regardless of the low temperature to which an underground or remotely located storage tank may be subjected.

Further objects will appear from the following description which, together with the accompanying drawing, discloses a preferred mode of carrying the invention into practice.

In this drawing:

Fig. 1 shows a somewhat schematic side elevation of the apparatus;

Fig. 2 shows an end view as seen from the right end of Fig. 1;

Fig. 3 shows a detail of a portion of Fig. 1 to illustrate the invention system as applied to a hot water boiler.

In general the invention contemplates the provision of the reserve or tempering tank intermediate the main supply and the burner, the reserve tank being equipped with an immersion type of electric heater and pipes for circulation of hot water or steam, whereby electricity or the other medium may be used interchangeably for heating the oil in the reserve tank to reduce its viscosity

2

to the point at which the burner may utilize the same efficiently. Automatic means are associated with the oil-heating means in order that a source of electricity may be connected to the immersion heater when the boiler is cold, i. e. when insufficient hot water or steam is available, or for cold starts after long periods of shut down, and then, upon the availability of this latter medium, due to operation of the boiler for the necessary length of time, the electrical means is switched off automatically and 5 the boiler is permitted to heat the oil. Additional means are provided for circulating heated oil back to the main supply to insure reasonably easy flow thereof to the reserve tank notwithstanding low ambient temperatures affecting the underground or remote storage tank or 10 the lines therefrom.

Where, in the description and claims, reference is made to "hot water" or "steam" or to a "hot water boiler" or "steam boiler," it will be understood that the terms are intended to contemplate not only "steam" or "hot water" 15 boilers for heating purposes, but other types of boilers (for example, high pressure boilers). Moreover the words "heating medium" are intended in their broadest sense as comprehending not only steam and hot water but any other fluid or gaseous medium which may be used 20 in a circulatory manner for heating. In the case of a steam system the return to the boiler will be understood as being condensate from a trap, and will correspond to the return side of a hot water system. Moreover, where reference is made to an "underground or remote" storage 25 tank, it will be comprehended that any main storage tank is intended, the substance being that a source of heavy fuel is available for supplying the intermediate, or reserve, tank. Additionally, this disclosure is also to be construed as embracing the same apparatus and system employed directly with the main storage tank, and thereby, if desired, eliminating the intermediate tank. Certain considerations may make it feasible to pre-heat 30 the oil in the main storage tank, and to use an intermediate tank simply to hold a supply of heated oil.

40 An important intended purpose of the reserve tank and its built-in allied apparatus is to maintain, condition and hold in reserve a sufficient quantity of residual oil in the boiler room for "cold start-ups." The oil therein contained can be readily heated by the electric immersion heater, the burner then started and the boiler brought up to sufficient heat prior to starting the circulating oil pump, thereby eliminating the excessive use of electrical power, by conversion of oil heating media from electricity to the oil itself through steam or hot water drawn 45 directly from the boiler, and in a minimum of time.

50 Turning to the drawing, a reserve tank 10 is shown as supported on four posts 11 upstanding from a sub-base 12 which may be, in turn, set on a conventional concrete foundation 13, or concrete floor near the burner-boiler unit in the boiler room which the invention apparatus is to serve.

55 Supported in a bushing or nipple 16 welded into one end of the tank 10 is an immersion type of electric heater 17, the junction box of the heater being indicated at 18. Conductors 19 feed from a control system to be referred to in detail hereinafter, and the source of current is indicated as leads 23—23.

Also supported on tank 10, by means of a bushing 25 is a heater 26 which may comprise a hairpin-shaped, 60 serpentine, or helically wound pipe coil, one end of which, say the feed, is indicated at 28 and the other end, the return, is indicated at 27. It will be understood that the tank 10 will, under normal operating conditions, be full of oil and further, that at no time, due to the elevation 65 of the interior termination 9 of the pipe 30 feeding heated oil to the burner 31, will it be possible to use the oil below the termination 9; thus assuring a sufficient quantity of

oil in tank 10, at all times, to cover the heaters 17 and 26. The usual overflow from the burner 31 is returned to the tank 10 through pipe 32.

The heavy oil from the main storage tank is received through a pipe 33, thence flows through filter 34, shut-off valve 35 and line 36 to the input port of the electric motor-driven pump 38. A branch 41 connects to a three-way valve 42, which is, in turn, connected to the lines 46 and 47, the former leading to the tank 10 and the latter tapping into the supply line 33.

A by-pass 48, relief valve 51 and line 52 is connected into line 36 to release safely over-pressure from line 41, i. e. from the pressure side of the pump 38 to the inlet 36. Vacuum gauge 56 will indicate the suction created by pump 38 through line 36, valve 35, filter 34, and supply fuel line 33 from the main storage tank.

Pressure gauge 57 will indicate the pressure head against which the pump 38 is working when forcing oil through line 41, three-way valve 42, line 46 into the tank 10.

In the event circumstances render it necessary to introduce light oil into the pump inlet to reduce the viscosity of the incoming oil or to thin the heavy oil in the bottom of the main storage tank, for example, when the storage tank is subjected to a temperature substantially below that for which the system is designed or the pour point of the oil is lower than usual, such thinning oil is preferably introduced from a reservoir (not shown) through line 53 and shut-off valve 54. From this point it can be forced by the pump 38 through line 41, three-way valve 42 (when properly positioned), line 47 and supply line 33 to the end of the suction inlet at the bottom of the storage tank, with valve 35 in closed position. This system can also be used to pump heated oil from tank 10 by closing valve 54 and opening valve 55 for the purpose of initiating proper oil flow through the system.

At this point it will be noted that the invention system is primarily adapted for operation in connection with a hot water or a steam boiler. Thus the heating medium will be introduced into the heater 26 via a supply line 61, and will exit via a line 62. If steam is the heating medium a trap or vacuum pump may be employed in a well known manner. By way of example a trap 63 is shown in the return line 62. In the case of hot water a return pump 60 is used (Fig. 3). In either event the arrangements are conventional and therefore will not be further elaborated upon.

To take care of the overflow, there is shown at 65 a return to the main supply tank. An immersion type thermostat is indicated at 66 to control the flow of hot water or steam from the boiler through heater 26 in accordance with the predetermined temperature setting for the oil in tank 10. Any conventional instrument may be employed, for example, one containing a temperature-responsive element in the form of a bi-metal strip, arranged to close and open a pair of contacts. Thermostat 66 may be designed for low voltage operation and its contacts are in circuit with a coil of a relay 70 whose armature 71 coacts with a front contact 72 and a back contact 73. Thus when the relay is deenergized ("cold" condition of the oil in the tank 10) a circuit is completed from an A. C. supply over conductors 23-23 for energizing the electrical heating element 17. When the oil reaches the temperature at which thermostat 66 is responsive the relay operates to disconnect the element 17 from the supply and armature 71 completes the circuit through its back contact 73 from leads 23-23 over conductors 75 and 76 to the valve 77 in the line 61 whereby steam is admitted to the heater 26. In the case of hot water operation the leads 75 and 76 take part in the same function but are connected to the pump 60. Such alternative is illustrated in Fig. 3 wherein the said leads are indicated at 75a and 76a.

If desired an immersion type reverse-acting thermostat (not shown) may be located at the boiler to pre-

vent the water circulator 60 from operating unless the water in the boiler is at the proper temperature.

The oil in tank 10 is continually heated by the automatically controlled electric heater 17 until hot water or steam is supplied by the burner-boiler unit, whereupon the heater 26 comes into play, thereby causing the electric heater 17 to cut off automatically and thus terminate consumption of electric power. As long as the burner-boiler unit provides the heating medium required, no electric power is consumed by the heater 17.

During normal operation of the system, pump 38 operates continuously to pump oil from the main storage tank through line 33, filter 34, valve 35 (opened) line 36, line 41, three-way valve 42 (properly positioned), line 46, into tank 10 where it is heated and discharged through line 65 back to the hot zone in the lower part of the main storage tank, except for the quantity extracted for use in the burner. Pump 38 is designed for handling from two to three times the quantity of oil which is consumed by the burner when running full capacity. Upon shutdown of the heating plant the initial conditions of the apparatus are restored in an apparent manner.

Assuming a sufficient volume of oil in the tank 10 for proper starting, the heater 17 will be switched on manually in accordance with the start of the heating period, this operation being effected through switch 80 and leads 23. After a sufficient time has elapsed to permit preheating of the oil in the tank 10, flow thereof to the burner may be initiated through line 30. Additional control apparatus not forming a part of the invention per se, are preferably arranged so that a room thermostat, a pressure-responsive device, or a temperature-responsive device, acting through a relay (not shown), conditions the oil burner motor for operation, and this motor circuit will also include a second contactor under the control of the temperature of the oil in the tank 10. Thus, when both contactors in the oil burner motor circuit are closed, the burner may operate. Obviously the viscosity of the oil exiting from the tank 10 will be a function of its temperature. Accordingly, unless such temperature is effective to close, through a suitable relay, the oil burner motor circuit, this circuit remains open.

In the foregoing, I have shown a particular embodiment of my invention in which it will be understood, of course, that I do not wish to be limited thereto since many modifications may be made, and I therefore contemplate by the appended claims to cover any such modifications as fall within the true spirit and scope of my invention.

Having thus described my invention, what I claim and desire to secure by Letters Patent is:

1. In a system including a main tank for receiving a supply of heavy fuel oil having a viscosity too high for direct utilization in an oil burner, an oil burner and a boiler heated by said burner, means for lowering the viscosity of the heavy oil to oil of viscosity which may be efficiently utilized by the burner comprising: a storage tank intermediate said main tank and burner, means for transferring the oil from the main tank to said intermediate tank, electrically-operated means operatively associated with said intermediate tank for heating the heavy oil to a lower viscosity for utilization by said burner, second heating means for the oil operatively associated with said intermediate tank and operated by fluid medium from the boiler, and means responsive upon the temperature of the fluid medium reaching a predetermined value for automatically terminating operation of said electrically-operated means and initiating operation of said second heating means.

2: In a system including a main tank for receiving a supply of heavy fuel oil, having a viscosity too high for direct utilization in an oil burner, an oil burner and a boiler heated by said burner, means for imparting utilizable viscosity to the oil as delivered to the burner, irrespective of the viscosity of the oil in the main tank comprising: a tank intermediate said main tank and said

burner, principal heating means for the oil incorporated with said intermediate tank and operated by the heating medium from the boiler during such time as the boiler is operating for reducing the viscosity of the oil to a utilizable level during such period as the boiler is operating normally, auxiliary heating means for the oil incorporated with said tank and operated by electricity, means operative in the absence of said heating medium for maintaining operation of said electrical heating means to reduce the viscosity of the oil in the intermediate tank to a utilizable level for direct delivery to the burner, and automatic means responsive upon the temperature of the heating medium reaching a predetermined value for initiating operation of the principal heating means and terminating operation of the electrical heating means.

3. In a system in accordance with claim 2 further characterized by a first conduit interconnecting said main and intermediate tank, and a second conduit connecting

5

10

15

said intermediate tank to said first conduit and valve means selectively operable for injecting heated oil into said first conduit for reducing the viscosity of the oil flowing from the main tank.
